**MEANS FOR SECURING A LIGHT REFLECTOR
 OR LIGHT DIFFUSER**
 Theophile A. Stiffel, 525 W. Superior St., Chicago, Ill.
 Filed Sept. 19, 1963, Ser. No. 309,922
 2 Claims. (Cl. 240—81)

This invention relates to means for securing a light reflector or light diffuser.

One of the objects of this invention is to provide improved means for detachably securing a light reflector or a diffusing shade to a lighting fixture.

Another object of this invention is to provide improved means for securing a light reflector or diffusing shade to a lamp or lighting structure.

Under present practice the light reflector or diffusing shade is connected to the shell or canopy of a floor or table lamp or lighting fixture by means of screws, which due to vibration or wear and tear have a tendency to loosen. This in turn will release the hold on the shade or reflector and permit it to vibrate with respect to its supporting structure. It also results in an ineffective securing means. With the present invention these objectionable features are eliminated in that set screws or other threaded fastening elements for fastening the shade are eliminated and in lieu thereof there is provided means for detachably securing a diffusing shade or reflector to a light fixture, such as a floor lamp, table lamp, or the like, merely by inserting the shade or diffuser in its socket or holder without requiring the use of any adjustable or manually operated adjusting parts.

Other objects will become apparent as this description progresses.

In the drawings:

FIG. 1 is a perspective view of a floor lamp showing the diffusing bulb or lamp shade supported in accordance with this invention.

FIG. 2 is an enlarged sectional view showing the manner in which the shade or lamp diffuser is supported in accordance with this invention.

FIG. 3 is a view taken on lines 3—3 of FIG. 2.

FIG. 4 is a fragmentary perspective view partially broken away showing the invention herein secured in the canopy.

FIG. 5 is a perspective view of the strip prior to its being shaped to form a circle or split ring.

FIG. 6 is a fragmentary sectional view showing the position of the shade or diffuser as it is either being inserted or being withdrawn, and

FIG. 7 is a sectional view of a modified construction. While this invention is shown in connection with a floor lamp, it will be understood that it may be used with table lamps, or with any other type of lighting fixture. Also, with this invention the shade or diffusing member may be supported suspended from above, that is, the shade and the means for supporting the shade may be inverted from that shown and same will be as effective in operation as that shown herein.

The conventional floor lamp designated by the numeral 10 has a post 12 on which is supported a canopy or shell generally designated by the numeral 14. The canopy or shell 14 is provided with an annular outwardly tapering shoulder 16 and an enlarged annular upper portion or mouth 18 which terminates in an inwardly extending annular flange or lip 20. The shape of the canopy or shell 14 is conventional.

Adapted to be supported within the upper end or mouth of the canopy or shell is an annular or ring-like shaped strip generally designated by the numeral 22, which is provided with means for detachably securing the diffusing bulb or shade member. The strip 22 is formed of a

2

springy metal material and is first shaped as shown in FIG. 5, that is, of rectangular shape, and is punched from the body of the strip to form a plurality of spaced inwardly extending ears, fingers, or lugs, generally designated by the numeral 24, thereby forming an opening or slot 25 in said body for each such finger. Each such finger is provided with an inwardly and downwardly inclined wall 26 which is bent to form a lower vertically extending wall 29 parallel with the body of the strip. The edge 30 is curvilinear.

After the strip has been formed, as shown in FIG. 5, it is then shaped to form a ring-like member which is split, such as best shown in FIGS. 3 and 4. In this form it is inserted in the mouth of the canopy or shell so that the lower edge of the strip 22 rests against the upper end of the shoulder 16 and the body of the strip is confined between the upper end of the shoulder 16 and the inwardly extending flange or lip 20 of the canopy. The annular strip must be reduced in diameter to be inserted into the mouth of the canopy due to the flange 20, and this is accomplished by overlapping the opposite ends 28 of the ring-like member 22.

After the ring-like member 22 is inserted in the canopy the springiness of the metal will cause it to occupy the space against the wall of the mouth of the canopy in a firm secured position. The opposite ends 28 of the annular ring-like member will be adjacent each other with a small spring therebetween, as best shown in FIG. 4. The ring-like member 22 thus in effect becomes a permanent part of the canopy and due to the springiness of the metal of the strip will cause it to expand within the mouth of the canopy and hug the wall firmly.

The conventional shade or diffusing reflector generally designated by the numeral 32 is provided with a neck designated by the numeral 34. A shoulder 36 is provided at the inner end of the neck and the neck curves inwardly and then outwardly to provide an enlarged beaded portion 38 at the outer end of the neck. To secure the shade in position the shade is inserted so that the neck of the shade enters the mouth of the canopy, as shown in FIG. 6, and the beaded portion 38 of the shade when inserted will engage the fingers 24, as shown in FIG. 6, to compress or push them outwardly in the direction of the slot or opening 25 to allow the beaded end 38 of the neck to pass inwardly beyond the ends of the fingers, after which the fingers 24 spring back to their normal position, shown in FIG. 2, in which they engage the curved surface above the beaded portion 38 to securely hold the shade in position and wherein the shoulder 36 rests on the inwardly extending flange 20 of the canopy 14.

With the inwardly extending fingers engaging the neck, as shown, the shade or deflector will be firmly secured in the mouth of the canopy sufficient to resist vibration between the shade and the canopy and sufficient to resist any accidental removal therefrom. It will be understood, however, that should it become necessary or desirable to remove the shade from the shell or canopy it may be removed by exerting a pulling force against the shade and with a sufficient pulling force the curved surface of the neck of the shade will cause the finger to be pressed outwardly in the direction shown in FIG. 6, sufficient to allow the shade to be pulled outwardly and removed.

Referring to the modification shown in FIG. 7, the ring-like shaped strip 22 has been eliminated and the ears, fingers, or lugs 24 have been punched or formed from the canopy or shell 14. The modified canopy or shell is designated by the numeral 14' and is formed preferably of metal and same is provided with the inwardly extending lip 20' and tapering shoulder 16', similar to that previously described. The body of the shell or canopy 14' is punched or formed with spaced inwardly extending ears, fingers or lugs generally designated by the numeral 24',

thereby forming an opening or slot 25' in said body for each such finger. Each such finger is provided with an inwardly and downwardly inclined wall 26', which is bent to form a lower vertically extending wall 29'. The edge 30' is curvilinear. The fingers 24' being formed of the metal material of the canopy have sufficient springiness or resiliency so that they will function in the same manner as that previously described in connection with the fingers 24. The shade or diffusing reflector 32 is supported and secured in the same manner as that previously described.

While the invention is shown as supporting the shade, it will be understood that the parts may be reversed from that shown, in other words, if it is desired to support the shade from overhead in a lighting fixture or the like, the ring-like member 22 and its supporting shell or canopy (or the modified construction of FIG. 7) will be positioned in a reverse position from that shown, in which case the shade will be supported in a suspended position from above. In this suspended position the parts will be exactly as shown herein except that they would be reversed. The shade would be held as effectively and efficiently as that shown in the drawings herein.

With this invention there is provided a very simple and inexpensive device which may be used in lieu of the conventional threaded screws, thereby overcoming the objections heretofore enumerated.

It will be understood that various changes and modifications may be made from the foregoing without departing from the spirit and scope of the appended claims.

What is claimed is:

1. Means for detachably supporting a shade or the like in relation to a lighting fixture having a canopy provided with a shoulder and an open end outwardly of said shoulder, with the shade having a neck portion and a bead at the outer end of the neck, said canopy having means wholly confined within said canopy and retained therewithin by said canopy between the shoulder and the open end, said means comprising a plurality of spaced inwardly extending fingers adapted to engage the bead of the shade for securing the shade when the neck of the shade is inserted into the canopy.

2. A structure defined in claim 1 in which the fingers are formed from the wall of the canopy.
